UNITED STATES PATENT OFFICE

2,646,480

FIRE ALARM SWITCH

Ira F. Pyles, Fairview, Ill.

Application August 29, 1950, Serial No. 182,080

1 Claim. (Cl. 200—138)

1

This invention relates to automatic electric fire alarms and more particularly to temperature controlled electric alarm sounding mechanisms operated by the alarm system and it has for its main object to provide a simple and inexpensive switching and sounding apparatus which is fool-proof and which is protected against all extraneous sources of disturbance and which may be mounted or installed anywhere and which will operate with all types of current.

A further object of the invention consists in providing a temperature sensitive sound alarm system which is operable by a thermic switch element preferably of the bimetallic type and which permits the use of any number of thermic switches in series with the alarm device, the latter producing sounds materially different from those produced by the customary alarm bell which are, therefore, easily distinguishable.

A further object of the invention consists in providing an automatic fire alarm system with bimetallic thermic units which, while protected against external mechanical influences, are so shaped that their formation produces considerable contact pressure and contact on relatively large area.

Further and more specific objects of the invention will be apparent from the following detailed specification.

The invention is described with reference to the accompanying drawings illustrating two embodiments thereof. It is, however, to be understood that the embodiments illustrated in the drawings are shown by way of example only and for the purpose of explaining the principle of the invention and the best mode of applying the principle. Further modifications will be obvious to the experts skilled in this art and a departure from the modifications shown in the drawings is, therefore, not necessarily a departure from the essence of the invention.

In the accompanying drawings:

Figure 1 is a diagram illustrating the use of thermic elements in connection with alarm devices of the customary type;

Figure 2 is an elevational cross section through one of the thermal responsive elements;

Figure 3 is a fragmentary elevational and sectional view similar to the view shown in Figure 2, the section being however taken along the line 3—3 of Figure 2;

Figure 4 is a diagrammatic partly sectional view of the thermal responsive elements and of the alarm device, all the views being partly sectional;

2

Figure 5 is a partly sectional front view of the alarm device, the section being taken along the line 5—5 of Figure 4;

Figure 6 is a plan view of the thermostatic element;

Figure 7 is a cross-sectional view through the bi-metallic strip with its contacts and also through the stationary contact with which the strip cooperates, the section being taken along the line 7—7 of Figure 6.

In the embodiment of the invention according to Figures 1, 2 and 3, a base member 10 of frusto-conical shape is provided which may be mounted on the wall or on the ceiling or on a horizontal board, ledge or shelf, and which carries the thermic element. Near the base of the frusto-conical element cuts may be provided for the introduction of the wires leading to the contact controlled by the thermic element. The top of the frusto-conical base member is covered with a base sheet 12 which is preferably encircled by a short cylindrical upstanding flange or collar 15.

The base sheet 12 carries an insulating plate 17 which is fixed to said base sheet by means of terminal posts 20, 21 surrounded by insulating flanged sleeves 19. These posts 20 and 21 also form the terminal posts for the two contact carrying members 14 which may consist of two short angle pieces one flange of which is held on the insulating plate 17 while the other flange is projecting at right angles thereto. The tips of the two angles 14 carry the contact buttons 16.

It will be understood that on account of the mounting of the contact carrier on the insulating plate the two contacts are normally insulated from each other.

Either on the base sheet 12 or preferably on the cylindrical flange 15 the bimetallic thermic element 30 is mounted by means of an insulated washer 22 and by means of rivets. This element is U-shaped, one leg 29 being longer and fixed to the flange 15 as above described, while the other element which is parallel thereto is shorter as shown at 28 and carries at its end an insulating longitudinal strip 24 which is fixed to the bimetallic strip by means of rivets or bolts. This insulating strip in its turn carries a transverse bridging contact member 25 which faces the contact buttons 16 and is adapted to be brought into operative contact with said buttons. The two legs 28 and 29 are joined by a sharp bend 27 the stretching of which under the influence of heat moves the shorter leg 28 towards the two

contacts 16. On account of the sharp curvature which may be selected in a suitable manner the transverse member 25 is applied against the contacts under considerable pressure which increases with the temperature to which the element is subjected. Under such pressure good contact is made even if the contact buttons 16 or the transverse contact bridge member 25 are no longer in a freshly polished condition.

A wire meshing 26 forming a closed cylinder with a closed dome-shaped top surrounds the thermic element and the contacts completely and protects these elements against mechanical influences and especially against accidental contact between the members 16 and 25 due to introduction of extraneous objects which may press against the thermic elements or which may accidentally penetrate into the space between the contacts 25 and 16.

Any number of thermic elements, generally designated by the reference numeral 8 in Figures 1 and 4 may be connected in parallel with alarm circuit 9. The alarm circuit may be branched off from any junction box 32 connected with the supply wires of a building. An ordinary alarm device 33 may be used in connection with the thermic switches and in this case is inserted into one of the branches of the alarm circuit 9. If a plurality of thermic elements is used they are all connected in parallel with the branches of the alarm circuit.

In Figures 4 to 7, a slightly different type of thermic element 8 and also a different alarm sounding device is shown.

The bimetallic strip 40 is mounted within an open box 39, preferably of insulating material through which air may freely circulate. The bimetallic element is thus exposed to the temperature of the air. The box 39 carries the post or pillar 42 on which the bimetallic strip 40 is mounted. The said strip in this case may be rectilinear and carries on its end a contact element 45 of a triangular cross section, Figures 4 and 7, which is attached to said strip. This wedge-shaped element is adapted to be pressed into the space between the two flaring contacts 46 and 47 which are mounted in the insulated box by means of rivets or bolts 43, 44 which also serve as terminal posts for the connection of the contacts 46, 47 with the branches of the alarm circuit. Obviously, when the bimetallic strip is flexed, the wedge-shaped bridge element 45 is pressed in between the flaring ends of contact members 46 and 47 under considerable pressure at higher temperatures. The two contacts 46 and 47 are thus bridged by the contact member 45 and, therefore, a connection is made between the two branches 9' and 9'' of the alarm circuit 9.

While the wedge-shaped bridge contact member 45 may be placed transversely with respect to the bimetallic strip as shown in Figures 6 and 7, the said element may also be placed longitudinally.

The two branches 9' and 9'' may be connected with one of the outlets of the network of the building.

One of the branches includes the alarm apparatus which in this case consists of a small electric motor 48 driving a shaft 49 on which is seated, by means of a sleeve 51 and a set screw 52, a disk 50. This disk 50 rotates within the body of a bell 55, carried by means of bolts and spacers 57 on a bail 58 which is fixed to the casing of the motor 48. As shown, the disk may rotate within the bell 55. The disk is provided with bolts 54

forming pivots and striker arms 56 which may swing around the bolts 54 and which may also be permitted some longitudinal movements by providing elongated bores through which the pivots 54 may pass on said striker arms.

A striker pin 60 may be arranged within the bell and may be attached to the bottom of the said bell. When, therefore, the motor starts to rotate the striker arms 56 assume a radial position and during rotation therefore will strike against the pin 60 and will thus produce, on account of the high frequency with which the pin is struck, a peculiar kind of sound which is distinguished from an ordinary sound produced by the customary alarm bell.

Obviously, also in the arrangement according to Figure 4, any number of thermic elements may be connected with the alarm circuit 9 in the manner shown in said figure, two elements being shown in order to illustrate said connection.

The operation of the system will be clear from the above description. In the event of flames striking the wire meshing or passing through the box 39 or in the event of such flames heating the air surrounding the wire meshing or passing through the box 39 the thermic element will operate and will produce a contact between the two contact buttons or flaring contacts, thus closing the alarm circuit 9. The alarm sounding device is in series with one of the branches of the alarm circuit is then operated and produces a sound in the manner already indicated.

It will be clear that all essential details may be changed without in any way departing from the invention as defined in the annexed claim.

Having described the invention, what is claimed as new is:

An alarm device comprising an elongated casing with parallel walls, an elongated substantially flat bimetallic strip arranged in substantial parallelism to the wall of the casing, a fixed support for said strip near one end of the casing, the other end being free and near the other end of the casing, a wedge shaped prismatic bridge contact of substantially triangular cross section carried by said bimetallic strip and fastened with its base at right angles to the bimetallic strip, the edge of the wedge running in substantial parallelism to the flat bimetallic strip, two elastic upstanding alarm circuit contacts insulated from each other and mounted on said insulating casing at a distance from each other on a wall of the casing parallel to and facing the bimetallic strip, contact surfaces arranged at the ends of the elastic upstanding alarm contact substantially parallel to the wedge surfaces, said alarm circuit contacts being placed close to each other, the contact surfaces of both alarm circuit contacts forming a wedge like structure having substantially the same cross section as the wedge shaped contact carried by the bimetallic strip, the latter when bent by unequal dilation pressing the wedge shaped prismatic contact into the wedge formed by the contact surfaces of the alarm circuit contacts.

IRA F. PYLES.
